DESK

Arthur P. Brashear, Jr., Temple, Tex., assignor to American Desk Manufacturing Company, Temple, Tex., a corporation of Texas

Application April 9, 1952, Serial No. 19,257

Term of patent 14 years

(Cl. D33—7)

To all whom it may concern:

Be it known that I, Arthur P. Brashear, Jr., a citizen of the United States, residing at Temple, county of Bell, State of Texas, have invented a new, original, and ornamental Design for a Desk, of which the following is a specification, reference being had to the accompanying drawing, forming a part hereof.

Fig. 1 is a perspective view of a desk embodying my new design, illustrating the top, front and one side of the desk.

Fig. 2 is an elevational view thereof showing the other side of the desk, and

Fig. 3 is a rear elevational view thereof.

I claim:

The ornamental design for a desk, as shown.

ARTHUR P. BRASHEAR, JR.
